UNITED STATES PATENT OFFICE

2,599,031

BUCKLE

Paul W. White, New Haven, Conn., assignor to
 Parva Products Company, Chicago, Ill., a corporation of Delaware

Application June 27, 1951, Serial No. 233,763

7 Claims. (Cl. 24—194)

1

This invention relates to shoe buckles, more particularly to slide type shoe buckles adapted to be mounted on shoe straps, and the invention has for an object the provision of a slide type shoe buckle which may be readily stamped from sheet metal and is of relatively small size but of sturdy construction, which is inexpensive to manufacture, and which is effective to clamp firmly or release readily a shoe strap.

The invention while applicable generally to slide buckles of the type disclosed in prior Patents No. 2,361,895, issued October 31, 1944, and No. 2,334,462, issued November 16, 1943, to Paul W. White, and No. 2,549,735, issued April 17, 1951, to Paul W. White and Joseph J. Schutz, is adapted and particularly designed for use as a shoe buckle. While slide buckles of the above type are generally suitable for their intended purpose, it has been found in many instances that the threads, which are conventionally used to secure the frame of a shoe buckle to one end of a supporting strap, are, upon continued use, cut by the end of the buckle slide as the buckle is opened and closed repeatedly with the result that the buckle frame is eventually severed from the strap end. Accordingly, it is a further object of the present invention to provide an improved shoe buckle that presents a neat and highly attractive appearance, that may be easily formed from sheet metal by a simple stamping operation, that may be quickly and economically assembled and is sturdy and reliable, and wherein the buckle slide is positively prevented from damaging the threads used to secure the buckle frame to one end of a strap.

It is a further object of the invention to provide a shoe buckle which obviates the necessity of perforating the shoe strap as is required when prong type buckles are employed.

According to one aspect of the invention a slide buckle is provided comprising a frame and a slide for cooperation with the frame, the frame and slide having side-bars and cross-bars defining strap receiving openings therethrough to receive a strap. The frame is provided with inwardly extending slide supporting shoulders, or runners, extending along the frame side-bars and one of the frame cross-bars adjacent one end of the shoulders is provided with a depressed strap attaching portion. The buckle slide is provided with offset projections, or ears, extending upwardly and rearwardly from one end of the slide side-bars to engage the end portions of the strap attaching cross-bar at points other than the depressed portion thereof, thereby to retain the slide within the frame for sliding movement along the shoulders. Another of the slide cross-bars is provided with a strap engaging portion extending upwardly out of the main plane of the slide for cooperation with another of the frame cross-

2

bars to clamp in adjusted position a strap threaded through the strap receiving openings. The buckle slide is provided with a pull-up cross-bar to effect movement of the slide to the clamping position, the pull-up bar having a portion extending out of the plane of the slide in the same direction as the strap engaging portion of said clamping cross-bar to prevent the insertion of the strap between the pull-up bar and the buckle frame.

For a more complete understanding of the invention, reference should now be had to the drawings, in which:

Fig. 1 is a top plan view of a buckle frame adapted for use in buckles embodying the present invention;

Fig. 2 is a bottom plan view of the frame shown in Fig. 1;

Fig. 3 is a top plan view of a slide adapted for cooperation with the frame shown in Figs. 1 and 2;

Fig. 4 is a left-hand end view of the slide of Fig. 3;

Fig. 5 is a right-hand end view of the slide of Fig. 3;

Fig. 6 is a side view of the slide of Fig. 3;

Fig. 7 is a longitudinal sectional view showing the frame and slide in assembled position with a strap partially threaded therethrough;

Fig. 8 is a sectional view similar to Fig. 7 but showing the buckle and strap in clamping relation;

Fig. 9 is a sectional view taken along the lines 9—9 of Fig. 8; and

Fig. 10 is a top view of the assembled buckle shown attached to the end of a strap and with the slide fully withdrawn.

Referring now to the drawing, the invention is shown as comprising a shoe buckle including a sheet metal frame 10 (Figs. 1 and 2), which may be conveniently and economically formed by a simple stamping operation, and a sheet metal slide 11 (Figs. 3, 4, 5, and 6) which may be formed by a similar stamping operation and which is adapted to cooperate with the frame 10. As shown, the frame 10 comprises a pair of side-bars 12 and 13 and a pair of cross-bars 14 and 15, the cross-bars 14 and 15 and the side-bars 12 and 13 forming a suitable strap receiving opening 17 through which a strap may be threaded. As shown in the drawing, the frame 10 is provided with a suitable extension comprising the side-bar extensions 18 and 19 which are inclined upwardly from the main plane of the frame, and an end cross-bar 16 which may be employed as a strap hold-down as best shown in Fig. 8. With the side bar extensions 18 and 19 inclined upwardly sufficient space is provided to permit the insertion of the strap under the hold-down bar 16 when the buckle is worn on the side of the shoe.

In this connection it will be understood that if the buckle is worn on the front of the shoe the side-bar extensions 18 and 19 may be substantially co-planar with the main plane of the frame 10 since the curvature of the ankle gives sufficient additional space to permit insertion of the strap under the hold-down bar 16.

As shown best in Fig. 2, the side-bars 12 and 13 are provided with rearwardly extending side wall portions 20 and 21 which form a recess suitable for receiving the slide 11. The side portions 20 and 21 are provided with inwardly extending lip portions 22 and 23 which extend along the side-bars 12 and 13 and rearwardly of the face of the buckle to provide slide supporting runners or shoulders. The forward cross-bar 14 of the frame 10 is generally inclined with respect to the plane of the shoulders 22 and 23, as shown best in Fig. 7, and the cross-bar 14 is provided with a curved upwardly extending tongue portion 25.

The strap attaching bar 15 of the frame 10 comprises an intermediate portion 26, which is depressed relative to the upper face of the buckle, and the side portions 27 and 28, which are inclined upwardly and connect the intermediate portion 26 with the upper face of the frame 10. As shown best in Fig. 9, the intermediate portion 26 of the cross-bar 15 is depressed sufficiently to position the bottom surface of this portion in substantially the same plane as the upper surface of the slide supporting shoulders 22 and 23. The portion 26 is provided with a forwardly projecting nub 29, for preventing unequal distribution of thread along the portion 26 as will appear more fully hereinafter.

Referring now to Figs. 3, 4, 5, and 6, the slide 11 comprises a pair of cross-bars 30 and 31 which are connected by suitable side-bars 32 and 33 to define a strap receiving opening 34. The cross-bar 31 is deformed slightly upwardly, as shown best in Fig. 4, to position this bar slightly above the main plane of the slide 11, and is provided with an upwardly extending portion 35 extending thereacross. As shown best in Fig. 5, the cross-bar 30 is provided with a depressed intermediate portion 36 which is deformed downwardly from the main plane of the slide 11 and is provided with the upwardly extending portion 37 formed centrally thereof. The side-bars 32 and 33 are disposed in edgewise relation extending out of the plane of the slide to form upwardly extending slide runners.

In order to provide a stop for the slide 11, suitable extensions are provided comprising the rearwardly extending side-bar portions 40 and 41 and the inner edges of the side-bar extensions 40 and 41 are turned upwardly to provide ear portions 42 and 43 which are offset inwardly relative to the slide runners 32 and 33 and project upwardly to engage the inclined portions 27 and 28 of the strap attaching bar 15 as shown best in Fig. 9.

In order to assemble the slide 11 in the frame 10, the slide 11 is inserted into the frame 10 and the slide supporting shoulders or runners 22 and 23 are thereafter deformed inwardly to the position shown in Fig. 2, thereby permanently retaining the slide 11 within the frame 10 as clearly shown in Fig. 9 of the drawing.

Once the slide and frame have been assembled the operation of the buckle thereby produced is in general similar to the operation set forth in the above referred to prior patents but by reason of the correlation and proportioning

of the parts in the present buckle an improved operation is obtained. The strap receiving openings 34 and 37 in the slide and frame respectively are in alignment to permit threading of a strap therethrough as shown in Fig. 7 and the cross-bars 30 and 31, respectively, constitute the pull-up bar and the clamping bar of the buckle. The upwardly extending portion 35 on the cross-bar 31 in cooperation with the inclined cross-bar 14 of the frame serves to clamp the strap in adjusted positions in the buckle whenever tension is applied.

In Figs. 7 and 8 the buckle is shown in connection with a strap comprising an attaching portion 50 which is suitably secured to the depressed portion 26 of the strap attaching cross-bar 15 of the buckle frame by the threads 51. The free end portion 52 of the strap is adapted to be threaded through and adjustably clamped in the buckle. In Fig. 7 the buckle is shown with the frame 10 and slide 11 in threading position with the free end 52 extending through the strap receiving apertures 34 and 37. When tension is applied to the strap, engagement of the strap portion 52 with the pull-up cross-bar 30 on the slide will cause the slide to move in a right hand direction from the position shown in Fig. 7 to the position shown in Fig. 8, in which position the strap is firmly clamped between the upstanding portion 35 of the cross-bar 31 on the slide 11 and the curved generally inclined surface formed by the forward cross-bar 14 and upwardly extending lip 25 of the frame 10. Thereafter the loose end of the strap portion 52 may be inserted beneath the hold-down bar 16 as shown in Fig. 8.

It will be noted that the strap engaging portion 35 is so correlated in height and location relative to the clamping portion of the cross-bar 14 as to provide a pressure angle of approximately 45 degrees. As described in prior Patent No. 2,549,735, issued April 17, 1951, to Paul W. White, a pressure angle in the neighborhood of 45 degrees permits satisfactory operation of the buckle to effect slip-free clamping of the strap while permitting ready release thereof. It will further be noted that by extending the runners 32 and 33 of the slide 11, upwardly from the general plane of the slide, the width of the slide is substantially reduced while permitting the proper spacing of the strap engaging portion 35 relative to the frame clamping bar 14 to provide the above described pressure angle. In this connection it will be understood that the tongue portion 25 is extended upwardly in the manner shown in order to increase the clamping surface available, but it will be understood that under certain conditions, i. e., for certain strap thicknesses or buckle sizes, the tongue portion 25 may be substantially reduced or eliminated without interfering with the satisfactory clamping operation thereof. It will also be understood that if the side runners 32 and 33 of the slide 11 were turned downwardly, the strap engaging portion 35 thereof would be positioned approximately at the level of the forward edge of the tongue portion 25 so that a butt-engagement of the strap by the portions 25 and 35 would be obtained which would not provide satisfactory clamping of the strap. Furthermore, if the strap is clamped between the extremities of the portions 25 and 35 the strap will bulge outwardly above the buckle and produce an unsightly protuberance which has a tendency to catch on surrounding objects and pull the buckle loose.

Whenever it is desired to release the strap from the buckle it is necessary to exert only a slight pull on the free end of the strap in a left hand direction as viewed in Fig. 8, thus to cause the slide 11 to move towards the threading or releasing position shown in Fig. 7.

As shown best in Figs. 9 and 10, the threads 51, which are used to secure the strap attaching portion 26 of the frame 10 to the strap end 50, are positioned between the separating nub 29 on the portion 26 and the upwardly inclined end portions 27 and 28 thereof. With this arrangement the thread remains distributed along the length of the strap attaching portion 26 and cannot bunch up at one corner thereof so that the buckle frame does not become loose or twist out of position. Furthermore, the buckle is prevented from moving transversely of the strap end 50 by the nub 29 so that the threads 51 cannot ride upwardly onto the inclined end portions 27 and 28. Since the offset ear portions 42 and 43 are the only parts of the slide 11 which strike the frame cross-bar 15 and these ear portions engage only the inclined end portions 27 and 28 thereof, the slide is positively prevented from striking and cutting the threads 51 as the buckle is opened and closed in use.

It will be observed that the upwardly extending portion 37 of the slide cross-bar 30 has the effect of preventing the insertion of the free end of the strap 52 between the frame cross-bar 14 and the cross-bar 30 of the slide 11. By reason of this construction there is very little possibility of threading the free end of the strap into the buckle incorrectly since it can be readily inserted only through the strap receiving openings 24 and 17.

While a particular embodiment of the invention has been shown, it will be understood, of course, that the invention is not limited thereto since many modifications may be made and it is, therefore, contemplated by the appended claims to cover any such modifications as fall within the true spirit and scope of the invention.

What is claimed as new and desired to be secured by Letters Patent of the United States is:

1. A slide buckle comprising, a frame, a slide for cooperation with said frame, said frame and said slide having side-bars and cross-bars defining strap receiving openings therethrough to receive a strap, said frame side-bars comprising side walls extending rearwardly of the face of said frame and inwardly turned slide supporting shoulders extending therealong, one of said frame cross-bars having a depressed central portion for attaching said frame to the end of a strap and having end portions inclined upwardly from said central portion, said central portion having a projecting nub intermediate the length thereof for preventing transverse movement of said frame relative to the end of the strap, whereby thread on said strap attaching portion is prevented from riding upwardly on said end portion, said slide having rearwardly extending projections thereon which are spaced apart by a distance greater than the width of said strap attaching portion and are positioned to strike the inclined end portions of said one frame cross-bar thereby to retain said slide within said frame for sliding movement along said shoulders while preventing said slide from striking thread positioned on the strap attaching portion of said one frame cross-bar, one of said slide cross-bars having a strap engaging portion extending out of the plane of said slide for cooperation with another of said

frame cross-bars to clamp in adjusted positions a strap threaded through said openings.

2. A slide buckle comprising, a frame, a slide for cooperation with said frame, said frame and said slide having side-bars and cross-bars defining strap receiving openings therethrough to receive a strap, said frame side-bars comprising side walls extending rearwardly of the face of said frame and inwardly turned slide supporting shoulders extending therealong, one of said frame cross-bars having a strap attaching portion positioned substantially in the plane of said shoulders and end portions inclined upwardly from said strap attaching portion, whereby thread on said strap attaching portion is prevented from riding upwardly onto said end portions, one of said slide cross-bars having a strap engaging portion extending out of the plane of said slide for cooperation with another of said frame cross-bars to clamp in adjusted positions a strap threaded through said openings, said slide having projections thereon extending rearwardly of said one slide cross-bar which are spaced apart by a distance greater than the width of said strap attaching portion and are positioned to strike the inclined end portions of said one frame cross-bar, thereby to retain said slide within said frame for sliding movement along said shoulders while preventing said slide from striking thread positioned on the strap attaching portion of said one frame cross-bar.

3. A slide buckle comprising, a frame, a slide for cooperation with said frame, said frame and said slide having side-bars and cross-bars defining strap receiving openings therethrough to receive a strap, said frame side-bars comprising side walls extending rearwardly of the face of said frame and inwardly turned slide supporting shoulders extending therealong, one of said frame cross-bars having a strap attaching portion positioned substantially in the plane of said shoulders and end portions inclined upwardly from said strap attaching portion, whereby thread on said strap attaching portion is prevented from riding upwardly onto said end portions, said slide side-bars comprising edgewise runners extending upwardly out of the plane of said slide, said slide having rearwardly extending side-bar extensions terminating in upstanding ear portions offset inwardly relative to said side-bar runners and adapted to engage the inclined end portions of said one frame cross-bar, thereby to retain said slide within said frame for sliding movement along said shoulders while preventing said slide from striking thread positioned on the strap attaching portion of said one frame cross-bar, one of said slide cross-bars having a strap engaging portion extending out of the plane of said slide for cooperation with another of said frame cross-bars to clamp in adjusted positions a strap threaded through said openings.

4. A slide buckle comprising, a frame, a slide for cooperation with said frame, said frame and said slide having side-bars and cross-bars defining strap receiving openings therethrough to receive a strap, said frame side-bars comprising side walls extending rearwardly of the face of said frame and inwardly turned slide supporting shoulders extending therealong, one of said slide cross-bars having a strap engaging portion extending out of the plane of said slide for cooperation with one of said frame cross-bars to clamp a strap therebetween, another of said frame cross-bars having a central strap attaching portion positioned substantially in the plane of said

shoulders and end portions inclined upwardly from said strap attaching portion, said strap attaching portion having a projecting nub intermediate the length thereof for preventing the unequal distribution of thread therealong, said slide side-bars comprising edgewise runners extending upwardly out of the plane of said slide, said slide having rearwardly extending side-bar extensions terminating in upstanding ear portions offset inwardly relative to said side-bar runners and adapted to engage the inclined end portions of said other frame cross-bar, thereby to retain said slide within said frame for sliding movement along said shoulders while preventing said slide from cutting thread distributed along said strap attaching portion of said other frame cross-bar.

5. A slide buckle comprising, a frame, a slide for cooperation with said frame, said frame and said slide having side-bars and cross-bars defining strap receiving openings therethrough to receive a strap, said frame side-bars comprising side walls extending rearwardly of the face of said frame and inwardly turned slide supporting shoulders extending therealong, one of said slide cross-bars having a strap engaging portion extending out of the plane of said slide for cooperation with one of said frame cross-bars to clamp a strap therebetween, another of said frame cross-bars having a central strap attaching portion positioned substantially in the plane of said shoulders and end portions inclined upwardly from said strap attaching portion, said strap attaching portion having a projecting nub intermediate the length thereof for preventing the unequal distribution of thread therealong, said slide side-bars comprising edgewise runners extending upwardly out of the plane of said slide, said slide having rearwardly extending side-bar extensions terminating in upstanding ear portions offset inwardly relative to said side-bar runners and adapted to engage the inclined end portions of said other frame cross-bar, thereby to retain said slide within said frame for sliding movement along said shoulders while preventing said slide from cutting thread distributed along said strap attaching portion of said other frame cross-bar, said slide having a second cross-bar serving as a pull-up bar to effect movement of said slide to clamping position when tension is applied to a strap threaded through said openings and having a portion extending out of the plane of said slide in the same direction as said strap engaging portion thereof to prevent the insertion of a strap between said second slide cross-bar and said one frame cross-bar.

6. A slide buckle comprising, a frame, a slide for cooperation with said frame, said frame and said slide having side-bars and cross-bars defining strap receiving openings therethrough to receive a strap, said frame side-bars comprising side walls extending rearwardly of the face of said frame and inwardly turned slide supporting shoulders extending therealong, one of said frame cross-bars having a strap attaching portion positioned substantially in the plane of said shoulders and end portions inclined upwardly from said strap attaching portion, said slide side-bars comprising edgewise runners extending upwardly out of the plane of said slide, said slide having rearwardly extending side-bar extensions terminating in upstanding ear portions offset in-

wardly relative to said side-bar runners and adapted to engage the inclined end portions of said one frame cross-bar, thereby to retain said slide within said frame for sliding movement along said shoulders while preventing said slide from striking thread positioned on the strap attaching portion of said one frame cross-bar, one of said slide cross-bars having a strap engaging portion extending out of the plane of said slide for cooperation with another of said frame cross-bars to clamp in adjusted positions a strap threaded through said openings, a second cross-bar on said slide having a central portion deformed oppositely out of the plane of said slide and serving as a pull-up bar to effect movement of said slide to clamping position when tension is applied to a strap threaded through said openings, said second slide cross-bar having a portion extending upwardly from the deformed portion thereof in the same direction as the strap engaging portion of said one slide cross-bar to prevent the insertion of a strap between said second slide cross-bar and said other frame cross-bar.

7. A slide buckle comprising, a frame, a slide for cooperation with said frame, said frame and said slide having side-bars and cross-bars defining strap receiving openings therethrough to receive a strap, said frame side-bars comprising side walls extending rearwardly of the face of said frame and inwardly turned slide supporting shoulders extending therealong, one of said frame cross-bars having a strap attaching portion positioned substantially in the plane of said shoulders and end portions inclined upwardly from said strap attaching portion, whereby thread on said strap attaching portion is prevented from riding upwardly onto said end portions, said slide having rearwardly extending projections thereon which are spaced apart by a distance greater than the width of said strap attaching portion and are positioned to strike the inclined end portions of said one frame cross-bar, thereby to retain said slide within said frame for sliding movement along said shoulders while preventing said slide from striking thread positioned on the strap attaching portion of said one frame cross-bar, one of said slide cross-bars having a strap engaging portion extending out of the plane of said slide for cooperation with another of said frame cross-bars to clamp in adjusted positions a strap threaded through said openings, said slide having a second cross-bar serving as a pull-up bar to effect movement of said slide to clamping position when tension is applied to a strap threaded through said openings and having a portion extending out of the plane of said slide in the same direction as said strap engaging portion thereof to prevent the insertion of a strap between said second slide cross-bar and said other frame cross-bar.
